UNITED STATES PATENT OFFICE.

JOSEPH EDWARDS AND JAMES R. F. KELLY, OF BROOKLYN, NEW YORK.

HOISTING AND CONVEYING APPARATUS.

SPECIFICATION forming part of Letters Patent No. 268,208, dated November 28, 1882.

Application filed September 21, 1882. (No model.)

To all whom it may concern:

Be it known that we, JOSEPH EDWARDS and JAMES R. F. KELLY, both citizens of the United States, residing at Brooklyn, in the county of Kings and State of New York, have invented new and useful Improvements in Hoisting and Conveying Apparatus, of which the following is a specification.

This invention relates to a hoisting and conveying apparatus containing a carriage which moves on suitable ways, and is provided with mechanism for raising, lowering, and conveying heavy articles.

The peculiar construction of the apparatus which forms the subject-matter of this application is pointed out in the following specification.

In the accompanying drawings, Figure 1 represents a side view of the entire apparatus. Fig. 2 is a side view of the brake mechanism 20 for checking the effect of the driving-power on a larger scale than the previous figure. Fig. 3 is a side view of the drums which carry the rope for transmitting motion to the carriage and to the hoisting-drums. Fig. 4 is a plan or top view of the same. Fig. 5 is a side view of the carriage. Fig. 6 is a plan or top view of the same. Fig. 7 is a longitudinal vertical section of the same in the plane $\alpha\alpha$, Figs. 6 and 8, showing the brake mechanism. Fig. 8 is a 30 plan or top view of the same.

Similar letters indicate corresponding parts.

In the drawings, the letter A, Fig. 1, designates a structure or store-house, which contains the hoisting apparatus, and which may be erected on a dock, if the hoisting apparatus is to be used for loading and unloading vessels, or which may be situated in any convenient position, as circumstances will dictate. In this structure is firmly secured a track, B, at a convenient height above the floor or ground, and on this track is placed the hoisting and conveying carriage C. (Best seen in Figs. 5, 6, 7, and 8.) This carriage is provided with four wheels, $a\ a\ b\ b$, which run on the track B, and it (the carriage) is drawn along on the track by means of an endless rope, c, which passes several times round two drums, d e, Fig. 5, and which connects with the driving mechanism, as will be hereinafter explained. The drum d is firmly mounted on a shaft, f, and on this shaft are also mounted two friction-wheels, g g, which serve to transmit the motion of the

drum d to the hoisting-drums h i. These hoisting-drums are mounted firmly on shafts h' i', respectively, and with each of the drums are 55 firmly connected two friction-wheels, h² i², respectively, in such a position that they can be thrown in or out of gear with the friction-wheels g g by the following mechanism: The shafts h' i' are mounted in eccentric boxes h³ i³, 60 which can be turned in their bearings by means of levers h⁴ i⁴. The levers h⁴, one on each side of the carriage, are connected by rods h⁵ with levers h⁶, mounted on a rock-shaft, h⁷, and they are also connected by rods h⁸ with levers 65 h⁹, mounted on a rock-shaft, h¹⁰, one of the levers h⁹ being elongated so as to form a hand-lever, which in the following description will be designated the "hand-lever h⁹." In the same manner the levers i⁴—one on each side of the 70 carriage—are connected by rods i⁵ with levers i⁶, mounted on a rock-shaft, i⁷, and they are also connected by rods i⁸ with levers i⁹, mounted on a rock-shaft, i¹⁰, one of the levers i⁹ being elongated so as to form a hand-lever, which 75 in the following description is designated the "hand-lever i⁹."

When the hand-levers h⁹ i⁹ are in the position shown in Figs. 5 and 6 the friction-wheels h² i² are out of gear with the friction-wheels g g, 80 and no motion is transmitted from the drum d to either of the hoisting-drums; but if the hand-lever h⁹ is drawn outward in the direction of the arrow marked near it in Fig. 5 the friction-wheels h² are thrown in gear with the 85 friction-wheels g g, and consequently receive motion from the drum d. The hand-levers h⁹ i⁹ are operated by men occupying the seats D D'; but in some cases it is desirable that the man occupying one of the seats—say the seat 90 D—shall be able to throw both hoisting-drums in or out of gear with the moving drum d. For this purpose I have mounted loosely on the rock-shaft h¹⁰ an additional hand-lever, i⁹⁰, 95 which connects by a rod, i⁹¹, with a lever, i⁹², mounted on the rock-shaft i⁷. (See Figs. 5 also 6.) The man occupying the seat D can throw the friction-wheels h² in gear with the moving drum d by drawing the hand-lever h⁹ outward, and by pushing in the additional 100 hand-lever i⁹⁰ he can throw the friction-wheels i² in gear with the moving drum. By similar means the friction-wheels h² may be operated from the seat D'. The drum h is provided

with a hoisting-rope, h^{12} , one end of which is firmly secured to a bolt, h^{13} , Fig. 6, while its other end is fastened to the drum h , so that by revolving this drum in the direction of arrow 5 1^* , Fig. 5, the rope is wound up, and by revolving the drum in the opposite direction the hoisting-rope is unwound. In the same manner a rope, i^{12} , is fastened at one end to the drum i and at its opposite end to a bolt, i^{13} , so 10 that when the drum i is revolved in the direction of arrow 2^* , Fig. 5, the hoisting-rope i^{12} is wound up, and vice versa. The articles to be raised or lowered are secured to pulley-blocks $h^{14} i^{14}$, which are placed into the bights 15 of the hoisting-ropes $h^{12} i^{12}$, Fig. 5.

On the rock-shafts $h^7 i^7$ are mounted brake-shoes $h^{17} i^{17}$, respectively, (see Figs. 5 and 5*) in such position that when the hand-lever h^9 is moved so as to throw the friction-wheel h^2 20 out of gear with the moving drum d the brake-shoes h^{17} are brought to bear upon the surfaces of the friction-wheels h^2 , and if the hand-lever i^9 is moved so as to throw the friction-wheels i^2 out of gear with the moving drum d 25 the brake-shoes i^{17} are applied to the surfaces of these friction-wheels. By means of this brake mechanism the weights suspended from the hoisting-ropes $h^{12} i^{12}$ can be maintained in an elevated position or permitted to descend 30 slowly. The brake-shoes are mounted on eccentric-bearings $h^{18} i^{18}$, so that they receive a positive motion in either direction if the shafts $h^7 i^7$ are turned.

In order to draw the carriage C along on the 35 track B, it is necessary to hold the drum d so that it cannot revolve, and if the endless rope c moves in the direction of arrow 1, Figs. 5 and 6, the carriage will be drawn along in the same direction, and vice versa. During the 40 time, however, when goods are to be raised or lowered, it is requisite that the carriage shall remain stationary. For these purposes a compound brake mechanism is applied, which is best seen in Figs. 7 and 8, and which will now be described.

On one side of the moving drum d is firmly secured a pulley, d' , Figs. 6 and 7, and round this pulley extends a flexible strap, d^2 , Fig. 7, the ends of which are fastened one to one and 50 the other to the other arm of a bell-crank lever, d^3 , which is firmly mounted on a rock-shaft, d^4 , that has its bearings in the frame of the carriage C.

On the rock-shaft d^4 are mounted two levers, d^6 , Fig. 8, which connect by rods d^7 with the upper ends of levers b' , which swing on pivots b^2 , secured in brackets attached to the brake-head b^3 , which carries the brake-shoes b^4 in position to act on the wheels $b b$ of the 55 carriage. The lower ends of the levers b' connect by rods b^5 with the brake-head a^3 , which carries the shoes a^4 in position to act on the wheels $a a$ of the carriage. One of the levers d^6 connects by a rod, d^8 , with the brake-lever 60 F, which is mounted loosely on the rock-shaft h^{10} . When the brake-lever is drawn in the direction of the arrow marked near it in Fig.

7 the shaft d is turned, the strap d^2 releases the pulley d' , and the brakes $a^4 b^4$ are applied to the wheels $a b$, the carriage is held stationary 70 on the track B, and the drum d is free to revolve. If the brake-lever E is moved in the direction opposite to said arrow, the brakes $a^4 b^4$ are taken off, and the strap d^2 is drawn up tight round the pulley d' , the drum d is prevented from turning, and the carriage is free 75 to follow the action of the endless rope c .

By referring to Fig. 5 it will be seen that the brake-lever E is in position to be operated by the man occupying the seat D. If desired, 80 a similar brake-lever may be applied near the opposite end of the carriage, so that the brake mechanism can also be controlled by the man occupying the seat D'.

The endless rope c receives its motion by 85 the mechanism represented in Figs. 1, 2, 3, and 4.

The shaft k , Fig. 1, is the driving-shaft, to which motion is imparted by a steam-engine or other source of power. From this driving-shaft motion is transmitted to the counter-shaft l , preferably by means of a chain and chain-wheels, and on the shaft l is mounted a chain-wheel, l' , from which motion is transmitted by a chain, l^2 , to a chain-wheel, m^2 , 90 mounted firmly on a counter-shaft, m , Figs. 3 and 4. This shaft is geared together with a counter-shaft, n , and both these shafts are mounted in eccentric boxes $m' n'$, respectively, 95 as seen in Fig. 3.

On each of the eccentric boxes is firmly mounted a lever, m^3 , and these levers connect by rods n^2 with levers n^3 , mounted on the eccentric-boxes n' . The levers n^3 connect by rods n^4 with levers o' , mounted on a rock-shaft, 100 o , and one of the levers o' is extended so as to form a hand-lever, which hereinafter will be termed the "hand-lever o' ."

On the shaft m is firmly mounted a friction-gear, m^5 , and a similar friction-gear, n^5 , is 110 mounted on the shaft n . If the hand-lever o' is brought into the position shown in Fig. 3, the friction-wheel n^5 is thrown in gear and the friction-wheel m^5 is thrown out of gear with a friction-gear, p^5 , which is firmly mounted on 115 a shaft, p ; but if the hand-lever o' is moved inward to the position indicated by the line o^* the friction-wheel m^5 is thrown in gear and the friction-wheel n^5 out of gear with the wheel p^5 , and if the hand-lever o' is brought 120 in a vertical position (indicated by line o^0 , Fig. 3) both friction-wheels $m^5 n^5$ are thrown out of gear.

On the shaft p is mounted a drum, p' , which is situated in a vertical plane passing through 125 the middle line of the track B, or nearly so, while the friction-gears $p^5 m^5 n^5$, the chain-wheel m^2 , and the chain l^2 are so placed that these parts do not interfere with the motion of the endless rope c and of the carriage C. (See Fig. 130 4.) The endless rope c is wound several times round the drum p' and round a secondary drum, q' , thence over a series of guide-rollers, c' , Fig. 1, to and over pulleys $c^2 c^3$, thence to and round

the drums d e in the carriage C, thence under and around a pulley, c^4 , and over pulley c^5 , back to the drum p' ; and both these drums are provided with a series of circular grooves for the reception of the rope. If the rope is wound round a single drum only, and a revolving motion is imparted to this drum, it happens that the drum revolves without imparting motion to the rope, and we have therefore found it necessary to employ two drums, p' q' , whereby, even if the rope is comparatively slack, it is not liable to remain stationary as long as the drum revolves. The employment of the two drums, however, enables us to keep the rope taut in the following manner: The drum q' is mounted on a shaft, q , and this shaft has its bearings in boxes q^2 , which can be moved in guideways q^3 , and are exposed to the action of set-screws q^4 . These set-screws are tapped into slides q^5 , which are fitted between the guideways q^3 , and are provided at their bottom with ledges q^6 , Fig. 3, which catch in recesses q^7 in the bottoms of the guideways q^3 , as shown more particularly in Fig. 3*. Bolts q^8 serve to secure the slides in the required position, and the boxes q^2 are fastened in the guideways by bolts q^9 . The object of this arrangement is to take up the slack of the endless rope c and to keep the same taut under all circumstances; and since this endless rope, on account of its great length, is liable to stretch considerably, the set-screws q^4 , if tapped in fixed supports, would not be sufficient to accomplish the desired object; but by means of the slides q^5 the set-screws can be always adjusted in such a position that they can be brought to act upon the boxes q^2 of the shaft q , and the endless rope can be held taut. At the same time, by means of the ledges q^6 , recesses q^7 , and bolts q^8 , the slides are retained firmly in the required position.

The friction-wheels m^5 n^5 , receiving their motion direct from the driving-power, revolve continuously, and if either of the friction-wheels is thrown in gear with the friction-wheel p^5 motion is transmitted to the drum p' , to the endless rope c , and through this endless rope to the hoisting mechanism in the carriage C. In order to be able to check the motion of the endless rope c immediately, when both the friction-wheels m^5 n^5 are thrown out of gear with the friction-wheel p^5 , a brake mechanism is applied, which consists of a strap, p^3 , embracing a pulley, p^4 , that is firmly secured to the drum p' , Figs. 2 and 4. The ends of the strap p^3 are secured to a disk, r' , on opposite sides of the center of the shaft r , on which said disk is mounted, so that by turning this shaft in one direction the strap releases the pulley p^4 and drum p' , and by turning said shaft in the opposite direction the strap hugs the pulley p^4 and checks the motion of the drum p' and endless rope c .

On the shaft r is firmly mounted a double-armed lever, r^2 , on one end of which is secured a weight, r^3 , while on its other end is fastened a curved saddle, r^4 . When the weight

r^3 is raised to the position shown in Fig. 2 the strap p^3 releases the pulley p^4 ; but when the weight r^3 is permitted to drop the strap p^3 is drawn up tight against the pulley p^4 . The position of the weight r^3 is governed by cams s' s^2 , which are secured on the end of a rock-shaft, s , at about right angles toward each other.

On the rock-shaft s is mounted a pulley, s^3 , on which are secured the ends of a rope, s^4 , which, after having been wound once or more times round said pulley, passes over guide-pulleys s^5 (see Fig. 1) and runs in close proximity to the carriage C, so that it can be reached by the men occupying the seats D D'. If the carriage moves in the track B in the direction of arrow 1, and it is desired to stop its motion, one of the men on the seats D D' pulls the rope s^4 in the direction of the arrow marked near said rope in Figs. 2 and 4. As the rock-shaft turns in the direction of arrow, Fig. 2, the cam s' releases the saddle r^4 , the weight r^3 turns the shaft r , and the strap p^3 hugs the pulley p^4 . At the same time the friction-wheel n^5 is thrown out of gear with the friction-wheel p^5 by the following mechanism:

On the shaft s is mounted a pulley, t , on which is secured a rope, t' , Fig. 4, which extends round guide-pulleys t^2 , and is secured to the hand-lever o' . When the rope s^4 is pulled in the direction of the arrows the pulley t turns, so as to move the rope t' in the direction of the arrow, and the hand-lever o' is moved to the position indicated by the line o^0 , Fig. 3, and the friction-wheel n^5 is thrown out of gear with the friction-wheel p^5 . If the rope s^4 is drawn still farther, the cam s^2 strikes the saddle r^4 , the weight r^3 is raised, and the strap p^3 releases the pulley p^4 . At the same time the hand-lever o' is moved to the position indicated by the line o^* , Fig. 3, the friction-wheel m^5 is thrown in gear with the friction-wheel p^5 , and the motion of the endless rope c is reversed. From this description it will be seen that the rope s^4 serves to check, stop, and reverse the motion of the endless rope c , and that said rope s^4 can be controlled by the men occupying the seats on the carriage C, or by a man stationed at the hand-lever o' , for if this hand-lever is moved its movement is transmitted to the brake-lever r^2 . The principal object of the rope s^4 , however, is to enable the men occupying the seats on the carriage C to reverse the motion of the endless rope c and of the carriage, for they have other means to stop and to check the motion of the carriage by means of the levers h^9 i^9 and the brake-lever E, as already described. From this description it will be seen that the men occupying the seats on the carriage are enabled to move the carriage to any part of the track B, and to impart motion to either of the hoisting-drums h i in either direction, so that they can raise a cask or other article by means of the hoisting-ropes h^2 i^2 , then move the carriage on the track B, and finally lower the casks into the hold of the vessel, or vice versa.

By referring to Fig. 1 of the drawings it will be seen that the track B is extended beyond the end of the structure or store-house A a sufficient distance to allow of moving the carriage over the hatchway of a vessel, or over a truck or wagon which may be intended to deliver or receive the goods. The extension of the track B is hinged, so that it can be turned up in a vertical direction, and is not in the way of bringing a vessel close up to the end of the store-house.

It is obvious that the endless rope and the driving mechanism which we have designed can be applied for other purposes besides the driving of the carriage C.

In place of the friction-gears, cog-wheels may be substituted, which are connected to their respective shafts by friction-couplings.

What we claim as new, and desire to secure by Letters Patent, is—

1. The combination, substantially as herein described, of the endless rope, the drums $p' q'$, each provided with a series of grooves to receive the successive coils of the rope as the same passes several times round the two drums, the guide-pulleys for supporting those portions of the rope outside of the drums $p' q'$, the carriage C, connected to the rope, and mechanism for imparting revolving motion to one of the drums.

2. The combination, substantially as herein-before described, of the endless rope c , the drums $p' q'$, round which said endless rope passes, the guideways q^3 , the boxes q^2 , which form the bearings for the shaft of the drum q' , and are adjustable in the guideways q^3 , the slides q^5 , which are adjustable in the guideways q^3 , and the set-screws q^4 , tapped in the slides q^5 .

3. The combination, substantially as herein-before described, of the endless rope c , the drums $p' q'$, round which said endless rope passes, the guideways q^3 , the boxes q^2 , which form the bearings for the shaft of the drum q' , and are adjustable in the guideways q^3 , the slides q^5 , the projections q^8 on these slides, the recesses q^7 in the guideways, and the set-screws q^4 .

4. The combination, substantially as herein-before described, of the endless rope c , passing round a drum, p' , the friction-wheel p^5 , mounted on the shaft of the drum p' , the friction-wheels $m^5 n^5$, which are geared together with the driving-power, the eccentric-boxes $n' m'$, which form the bearings for the shafts of the friction-wheels $m^5 n^5$, the levers $m^3 n^3$, connected to the eccentric boxes, and the hand-lever o' , connected to the levers $n^3 m^3$, whereby either of the friction-wheels $m^5 n^5$ can be thrown in or out of gear with the friction-wheel p^5 .

5. The combination, substantially as herein-before described, of the endless rope c , passing round a drum, p' , the friction-wheel p^5 , mounted on the shaft of the drum p' , the friction-wheels $m^5 n^5$, which are geared together with the driving-power, the hand-lever o' for throwing the friction-wheels $m^5 n^5$ in or out of gear with the friction-wheel p^5 , and the brake-lever

r^2 , connected to the hand-lever o' for the purpose of checking the motion of the endless rope c whenever both friction-wheels $m^5 n^5$ are thrown out of gear with the friction-wheel p^5 .

6. The combination, substantially as herein-before described, of the endless rope c , passing round a drum, p' , the friction-wheel p^5 , mounted on the shaft of the drum p' , the friction-wheels $m^5 n^5$, which are geared together with the driving-power, the hand-lever o' for throwing the friction-wheels $m^5 n^5$ in or out of gear with the friction-wheel p^5 , the pulley p^4 , secured to the drum p' , the strap p^3 , embracing the pulley p^4 , and having its ends fastened to a disk, r' , on opposite sides of its center, the weighted lever r^2 , mounted on the shaft of the disk r' , the cams $s' s^2$, which are secured to a rock-shaft, s , and act upon the weighted lever r^2 , and the rope t' , which connects the rock-shaft s with the hand-lever o' , whereby the brake is applied whenever the hand-lever o' is thrown in its central position and taken off when the hand-lever o' is moved in either direction to one of its extreme positions.

7. The combination, substantially as herein-before described, of the endless rope c , passing round a drum, p' , the friction-wheel p^5 , mounted on the shaft of the drum p' , the friction-wheels $m^5 n^5$, which are geared together with the driving-power, the hand-lever o' for throwing the friction-wheels $m^5 n^5$ in or out of gear with the friction-wheel p^5 , the brake-lever r^2 , the carriage C, hitched to the endless rope c and moving on a track, B, and the rope s^4 , extending in close proximity to the carriage and connecting with the hand-lever o' and brake-lever r^2 .

8. The combination, substantially as herein-before described, of the endless rope c , mechanism, substantially such as described, for imparting motion to this rope in either direction, the carriage C, moving on the track B, the drum d , round which the endless rope passes, and which is mounted on a shaft which has its bearings in the carriage C, the friction-wheels $g g$, mounted on the shaft of the drum d , the hoisting-drums $h i$, mounted on shafts $h' i'$, the friction-wheels $h^2 i^2$, connected to the hoisting-drums, mechanism, substantially such as herein-described, for throwing the friction-wheels $h^2 i^2$ in or out of gear with the friction-wheels $g g$, the hand-levers $h^9 i^9$ for operating this mechanism, and the brake-shoes $h^{17} i^{17}$, connected to the hand-levers $h^9 i^9$.

9. The combination, substantially as herein-before described, of the endless rope c , mechanism, substantially such as described, for imparting motion to this rope in either direction, the carriage C, moving on the track B, the drum d , round which the endless rope passes, and which is mounted on a shaft which has its bearings in the carriage C, the friction-wheels $g g$, mounted on the shaft of the drum d , the hoisting-drums $h i$, mounted on the shafts $h' i'$, the friction-wheels $h^2 i^2$, connected to the hoisting-drums, the eccentric boxes $h^3 i^3$, forming the bearings of the shafts $h' i'$, the levers $h^4 i^4$, con-

nected to said eccentric boxes, and the hand-levers $h^9 i^9$, connected to the levers $h^4 i^4$.

10. The combination, substantially as hereinbefore described, of the endless rope c , mechanism, substantially such as herein described, for imparting motion to this rope in either direction, the carriage C , moving on the track B , the drum d , round which the endless rope passes, the friction-wheels $g g$, mounted on the shaft of the drum d , the hoisting-drums $h i$, mounted on shafts $h' i'$, the friction-wheels $h^2 i^2$, connected to the hoisting-drums, the eccentric boxes $h^3 i^3$, forming the bearings of the shafts $h' i'$, and the hand-lever i^{90} , acting on the eccentric boxes $h^3 i^3$, so as to throw the friction-wheels h^2 in and the friction-wheels i^2 out of gear with the friction-wheels $g g$, or vice versa.

11. The combination, substantially as hereinbefore described, of the endless rope c , mechanism, substantially such as herein described, for imparting motion to this rope in either direction, the carriage C , moving on the track B , the drum d , round which the endless rope passes, the brake applied to the drum d , the brakes applied to the wheels of the carriage C , and the hand-lever E for controlling all these brakes.

12. The combination, substantially as hereinbefore described, of the endless rope c , mechanism, substantially such as herein described, for imparting motion to this rope in either direction, the carriage C , moving on the track B , the drum d , round which the endless rope passes, the strap d^2 , embracing a pulley d' , secured to the drum d , the rock-shaft d^4 , carrying a bell-crank lever or equivalent device for controlling the action of the strap d^2 upon the pulley d' , the levers d^6 , mounted on the rock-shaft d^4 , the rods d^7 , extending from these levers to levers b' , mounted on the brake-head b^3 , the rods b^5 , extending from the levers b' to the brake-head a^3 , and the rod d^5 , extending from one of the levers d^6 to the hand-lever E .

In testimony whereof we have hereunto set our hands and seals in the presence of two subscribing witnesses.
